FLOTATION MACHINE

Roger Dering, Salt Lake City, Utah, assignor to
 Combined Metals Reduction Company, Salt
 Lake City, Utah, a corporation of Utah

Application May 12, 1949, Serial No. 92,868

7 Claims. (Cl. 209—169)

1

This invention relates to flotation machines, extensively employed for the separation of valuable constituents from ores or other materials.

The art of flotation usually involves both the aeration and agitation of a so-called "pulp," which is a liquid suspension of finely ground material containing the valuable constituents to be recovered. Chemical reagents designed to produce a froth and to aid the froth in retaining valuable particles adhering thereto become part of the pulp in the flotation procedure. The froth which carries the valuable concentrates is recovered as the end product of the operation.

Flotation machines as customarily constructed provide for aeration and agitation of the pulp, in common, within a single chamber, and carry out both operations simultaneously by the same impeller.

In accordance with the present invention, however, aeration is accomplished in one chamber by an impeller especially designed for aeration purposes, and agitation of the aerated pulp is carried out in a second chamber by a second impeller. Both chambers and both impellers are part of the general flotation machine structure, and the aerated pulp passes into the agitation chamber by way of the second or agitation impeller. Provision is made for controlled recirculation of pulp from the agitation chamber back through the aeration chamber.

Principal objects of the invention are:

To provide a flotation machine having a high operative efficiency, simplicity of construction, and economy of floor space occupied.

To provide such a machine which will require few repairs and will have a long operating life.

Further objects and features of the invention will become evident as the description proceeds with respect to that presently preferred specific construction illustrated in the accompanying drawings by way of exemplifying the novel concepts involved rather than by way of limitation.

In the drawings:

Fig. 1 represents a fragmentary top plan view of a bank of flotation cells comprising a series of the machines of the invention, the first machine or cell being shown in entirety except for the impeller drive mechanism;

Fig. 2, a longitudinal vertical section taken on the line 2—2 of Fig. 1;

Fig. 3, a transverse vertical section taken on the line 3—3 of Fig. 1 but illustrating in elevation the impeller drive mechanism which is not illustrated in the foregoing figures;

Fig. 4, an enlarged detail view in central vertical section of the aeration impeller;

2

Fig. 5, a cross-section taken on the line 5—5 of Fig. 4; and

Fig. 6, a cross-section taken through the agitation impeller on the line 6—6 of Fig. 2 and drawn to a scale somewhat less enlarged than Figs. 5 and 6.

Referring to the drawings: the machine illustrated comprises a bank of flotation cells 10, the tailings from one cell passing into the next succeeding cell over a weir 11 in customary manner.

Each cell is equipped with an inlet 12 disposed at the lower part of an intake column 13 defined at the front of the cell. In the instance of the first cell of the series the intake column is defined by suitably provided walls, as shown. In succeeding cells the intake column is defined in part by the weir 11.

The individual cell 10 comprises a container for the flotation pulp flowing into the cell through inlet 12, such container being made up of a base portion 14, which partially defines a pulp flow conduit or aeration chamber 15, and of a superimposed portion 16, which partially defines pulp recirculation columns 17 at opposite sides of the cell.

Advantageously, the pulp columns 17 flare outwardly as they rise to the level of froth-discharge lips 18, and, at their bottoms, have controlled communication with the aeration chamber 15 through longitudinally-extending recirculation passages 19. The degree of opening of such passages is controlled by butterfly dampers 20, which are arranged for adjustment manually by means of respective handles 21, Fig. 1.

The aeration chamber 15 and oppositely disposed pulp columns 17 are further defined by the outer walls of an inner container 22, which provides an agitation chamber 23 for aerated flotation pulp.

The bottom of this second or inner container 22 is formed by a cheek plate tray 24, supported by inturned flanges 22a, and has a centrally-disposed opening into which fits a depending portion of the agitation impeller described hereinafter.

The top of container 22 is open, and is disposed well below the level of froth-discharge lips 18 to provide for adequate froth migration from the bubble column established within container 22, across pulp columns 17, and over froth-discharge lips 18 into froth launders 25 which extend longitudinally of the bank of cells 10, along opposite sides thereof.

The intake column 13 advantageously comprehends the width of agitation chamber 23, an end wall 22b of the inner container 22 separating the two. Likewise, a stilling well 26, defined at the

opposite end of the cell between the opposite end wall 22c of the inner container and the tailings-overflow weir 11, advantageously comprehends the width of agitation chamber 23. A tailings-discharge opening 27, disposed at a suitably low level in the end wall 22c, provides for passage of spent pulp from agitation chamber 23 into stilling well 26, and so into the intake column 13 of the next cell of the series.

As in the conditioning machine forming the subject of my copending application for patent, Serial No. 89,632, filed Apr. 26, 1949, wherein are disclosed concepts generic to the subject matter of the present application, aeration is accomplished within the pulp flow conduit or aeration chamber by means of an aerating impeller, and the aerated pulp is drawn into and agitated within the agitation chamber by means of an agitating impeller.

For this purpose, a tubular drive shaft 30 extends downwardly through agitation chamber 23 and through the center of the aforementioned centrally-disposed opening in cheek plate tray 24 to a termination spaced upwardly from the bottom of the aeration chamber 15.

Fixed to the drive shaft 30 so its depending annular lip 31a is snugly rotatable within the aforesaid opening in cheek plate tray 24, is a hollow disk type agitation impeller 31 having discharge passages 32, Fig. 6, radiating from the intake opening 33 defined by annular lip 31a. Swirl grids 34 rising from an annular swirl grid plate 35 are advantageously provided to stabilize the agitating action of impeller 31.

Fixed to the end of drive shaft 30 below impeller 31 and within aeration chamber 15 is disk-type aeration impeller 36.

Such impeller 36 is preferably of a novel construction, affording superior dissemination of air in the pulp contained by aeration chamber 15. As illustrated, Figs. 4 and 5, the impeller 36 has a receiving recess 37 centrally located in its upper surface, into which is tightly fitted the lower end of the tubular drive shaft 30. The recess 37 is preferably countersunk to provide a chamber 38 from which lead a plurality of radial-air-ejector passages 39, desirably of tubular formation as shown. The circumferential periphery of impeller 36 is symmetrically notched to provide ports of entry 40 for the air as it discharges from the respective ejector passages 39, it being understood that such passages open into the respective ports of entry. For obtaining an especially effective mixture of air with the pulp, such ports of entry 40 are formed with a radial leading portion 40a and a concavely arcuate trailing portion 40b, all as set forth in my aforementioned patent application S. N. 89,632.

For mixing the reagents with the flotation pulp, a tube 41 of smaller diameter than the tubular drive shaft 30 is inserted longitudinally and concentrically within such shaft so as to terminate within aeration impeller 36 preferably just above chamber 38 thereof, as illustrated.

The drive shaft 30 is mounted for rotation within an elongate bearing assembly 42, making up part of a supporting superstructure 43 which rests upon the upper portion 16 of the cell, as by means of cross-beams 44. Rotation of shafts 30 may be effected by any suitable means, for example by an electric motor (not shown) belted to a drive pulley 45 which is rigidly fixed to the shaft.

The air is delivered to chamber 38 of aeration impeller 36 through the annular longitudinal

passage 46 defined between reagent delivery tube 41 and the interior walls of drive shaft 30. For introducing air into passage 46, a pipe-fitting 47 is mounted at the upper end of drive shaft 30 by means of a conventional rotary joint assembly 48. A pipe 49 supplies air to pipe-fitting 47, and thus to passage 46 of the tubular drive shaft 30, from any suitable source. Preferably the source is a pressure source, such as an air compressor, so there will be a forcible introduction of air into the centrifugal aeration impeller 36.

In operation, flotation pulp is continuously introduced into the cell 10 through the intake column 13 and inlet 12 thereof, to form a body of pulp within both the aeration chamber 15 and the agitation chamber 23, as well as the respective pulp columns 17 and stilling well 26. Outflow occurs over the weir 11.

Rotation of the tubular drive shaft 30, together with supply of air and reagents through the passages above-described, effects a substantially uniform aeration of the pulp in chamber 15, as well as thorough intermixiture of the reagents therewith. Furthermore, such rotation of drive shaft 30 produces a simultaneous and corresponding rotation of agitation impeller 31, which, in effect, sucks aerated pulp from chamber 15 and forcibly discharges it into the body of pulp within agitation chamber 22, thereby not only agitating such pulp so that bubbles carrying valuable particles picked up from the pulp may easily rise to the surface and form a thick layer of froth 50, but also acting upon such aerated pulp to break up large bubbles into small bubbles which make up a copious, heavily-laden froth concentrate. The swirl grids 34 act to stabilize the agitated pulp and to cause a substantially vertical circulation thereof, so the mineral-laden bubbles will rise to the surface in substantially direct lines.

Recirculation of aerated and agitated pulp through the aeration and agitation chambers may be effected in controlled amount through the respective pulp columns 17 by means of suitable settings of the damper valves 29.

Spent pulp from a low point in the bubble column of container 22 flows out of the cell 10 through the tailings-discharge opening 21 for similar treatment in a subsequent cell of the series, or for discard in the case of the final cell, the outflow passing through the stilling well 26 and over weir 11, in conventional manner. A sand gate 51 permits controlled outflow from aeration chamber 15 directly into the lower part of the intake column 13 of the succeeding cell of the series.

It should be noted that the location of the agitation impeller 31 within and immediately above the passage providing flow communication from the aeration chamber to the agitation chamber, and the disposition of the aeration impeller 36 therebelow, provide an especially efficient action for the machine as a whole.

Whereas this invention is here illustrated and described with respect to a presently preferred specific construction thereof, it should be understood that various changes may be made therein and various other constructions may be resorted to on the basis of the teachings hereof, by those skilled in the art, without departing from the protective scope of the following claims.

I claim:

1. A flotation machine, comprising an open container for pulp; pulp inflow means com-

municating with one end of said container adjacent the bottom thereof; tailings outflow means leading from said container at the other end thereof; a second and smaller open container for pulp disposed within the first container and spaced upwardly from the bottom and inwardly of side walls thereof to define a pulp flow conduit below the bottom of said second container, in flow communication with said pulp inflow means, and to define, further, pulp recirculation columns between side walls of said first and second containers, in flow communication with the open top of said second container and with said pulp flow conduit; pulp aerating means operably disposed within said pulp flow conduit; passage means leading through the said bottom of the second container; an agitation impeller operatively disposed within said second container above said passage means and adjacent the said bottom thereof, so as to be completely submerged and surrounded by liquid, without access to the atmosphere, during operation of the machine, for aiding elevation of pulp through said passage means and for agitating said pulp within the said second container; and froth overflow lips defined along the upper margins of side walls of said first container, said second container being of effectively less height than said first container to provide for recirculation flow of pulp over side walls thereof below said froth overflow lips and underlying the overflowing froth column.

2. The combination recited in claim 1, wherein the aerating means comprises an aeration impeller and communicating source of air disposed within the pulp flow conduit directly below the agitation impeller.

3. The combination recited in claim 2, wherein both impellers are fixed to a tubular drive shaft extending vertically within both chambers, and wherein air is supplied to the aeration impeller through said drive shaft.

4. A flotation machine, as defined in claim 1, wherein there are provided, in the pulp circulation columns, valve means for controlling flow of pulp.

5. A flotation machine as defined in claim 1, wherein the agitation impeller has a depending, annular lip portion extending through the passage means in the bottom of the second container, in substantially contiguous relationship with the defining walls of said passage means.

6. The combination recited in claim 5, wherein the drive shaft is hollow for the delivery of air

to the aeration impeller, and the aeration impeller comprises a disk having a retrocedent rim providing a plurality of enlarged ports of entry inwardly of the circumferential periphery of the disk for the air as it is discharged into the pulp, and a plurality of air-ejecting, tubular passages extending from intake communication with the hollow interior of the drive shaft to outlet communication with the respective ports of entry.

7. A flotation machine, comprising a container for flotation pulp, a substantially horizontal wall intermediate the depth of said container dividing said container into a lower pulp compartment, serving as an aeration chamber, and into an upper pulp compartment; a pair of mutually spaced, substantially vertical walls rising within said upper pulp compartment from said horizontal wall to a level below the froth-outflow level of said container and defining therebetween an agitation chamber immediately above said aeration chamber, said vertical walls being spaced from side walls of said container to define pulp-recirculation passages at opposite sides of said agitation chamber and in communication with said aeration chamber; froth discharge means disposed above said passages; an opening in said horizontal wall establishing communication between said aeration chamber and said agitation chamber; an agitation impeller rotatable within said opening; and means for aerating pulp within said aeration chamber.
